CLAIM

The ornamental design for a pipe fitting as shown and described.

DESCRIPTION

FIG. 1 is a perspective view of a pipe fitting, showing the new design;

FIG. 2 is a front view thereof;

FIG. 3 is a rear view of thereof;

FIG. 4 is a left-side view thereof;

FIG. 5 is a right-side view thereof;

FIG. 6 is a top plan view thereof; and,

FIG. 7 is a bottom view.

The broken lines depict portions of the pipe fitting that form no part of the claimed design.

1 Claim, 7 Drawing Sheets
